United States Patent Office

Des. 211,646
Patented July 9, 1968

211,646

MAGNETIC TAPE RECORDER DECK

Eugene R. P. Leman, Los Gatos, Calif., assignor to International Video Corporation, Mountain View, Calif., a corporation of California

Filed Sept. 13, 1967, Ser. No. 8,578

Term of patent 14 years

(Cl. D26—14)

FIG. 1

FIG 2

FIG. 3

FIG. 1 is a perspective view, taken from the front and slightly above and to the right of center, of a magnetic tape recorder deck showing my new design;

FIG. 2 is a top plan view of the magnetic tape recorder deck of FIG. 1; and

FIG. 3 is a perspective view taken from the rear and slightly above and to the right of center, of the magnetic tape deck of FIG. 1.

The broken lines are shown for illustrative purposes only.

I claim:

The ornamental design for a magnetic tape recorder deck, substantially as shown and described.

UNITED STATES PATENT OFFICE
CERTIFICATE OF CORRECTION

Design No. 211,646

July 9, 1968

Eugene R. P. Leman

It is certified that error appears in the above identified patent and that said Letters Patent are hereby corrected as shown below:

In the grant, lines 2 and 13, and in the heading to the drawing and printed specification, lines 3 and 4, "International Video Corporation" should read -- International Video Corporation --.

Signed and sealed this 13th day of January 1970.
